Attorney

UNITED STATES PATENT OFFICE.

FRANK B. ROSS, OF CAPE GIRARDEAU, MISSOURI.

VULCANIZER FOR RUBBER BOOTS AND SHOES.

1,311,012.

Specification of Letters Patent. Patented July 22, 1919.

Application filed December 31, 1918. Serial No. 269,165.

To all whom it may concern:

Be it known that I, FRANK B. Ross, a citizen of the United States, residing at Cape Girardeau, in the county of Cape Girardeau and State of Missouri, have invented certain new and useful Improvements in Vulcanizers for Rubber Boots and Shoes, of which the following is a specification.

This invention relates broadly to improvements in vulcanizers and more particularly relates to a vulcanizer for boots and shoes.

It is the primary object of this invention to provide a device of the above mentioned character designed for vulcanizing rubber or plastic composition soles on boots and shoes, the component parts being of novel construction and adjustable relative to each other to permit of the application and removal of shoes to and from the supporting tree.

It is an additional object of this invention to provide a device of the above mentioned character wherein improved means is employed for guiding the mold and for applying heat and pressure to the mold.

The invention also embraces the provision of a device of the above mentioned character wherein the main support is of novel construction and is designed to effectively support the shoe supporting tree and the guiding means for the mold.

Among the other aims and objects of this invention may be recited the provision of a device of the above mentioned character wherein the number of parts are comparatively few, the construction simple, the cost of production low and the efficiency high.

Other objects, as well as the nature, characteristic features, and scope of this invention will be more readily understood from the following description taken in connection with the accompanying drawings and pointed out in the claims, forming a part of this specification.

The invention is clearly illustrated in the accompanying drawings, in which:—

Figure 1 is a side elevation showing the improved vulcanizing device,

Fig. 2 is a front elevational view thereof, Fig. 3 is a transverse section taken on line 3—3 of Fig. 1, and

Fig. 4 is a top plan detail of a modified form of mold.

Similar characters of reference are employed in all of the above described views, to indicate corresponding parts.

Referring now, more particularly, to the accompanying drawings there is provided a stand consisting of a base 1 from which rises a standard 2 on the upper edge of which is supported an inverted shoe supporting tree 3. A shelf 4 is connected to the standard 2 and supported in a laterally extended position with respect to the standard by means of braces 5 while mounted on the upper surface of the shelf are spaced brackets 6 to which are pivoted as by pins 7 the adjacent terminal ends of the side portions or legs 8 of the substantially inverted U-shaped supporting and guiding frame generally designated 9. In this connection it is to be noted that the shelf 4 is positioned beneath the front part of the shoe supporting tree 3 while the side or leg portions 8 are designed to straddle the legs with respect to the front portion of the tree 3, the arrangement being indicated in the drawings.

Arranged between the side or leg portions 8 of the movable frame 9 is a mold 10 consisting generally of a rectangular hollow body the under surface of which is recessed as at 11 to conform to the configuration of half of the sole of a shoe, it being necessary to arrange the mold above the outer portion of the tree 3 so that the recessed portion 11 will be accommodated about the sole of a shoe (not shown) adapted to be supported on the tree. The mold is formed on its opposite sides and medially of its ends with notched lugs 12 designed to slide into engagement with the side or leg portions 8 so as to be guided thereby.

In order to apply heat to the mold an inlet pipe 13 is mounted in one end of the tree and is fitted with a manually operable valve 14 controlling the passage of heat through the pipe into the casing while the opposite end of the stem has a coupling 15 mounted thereon which in turn is designed to engage a nipple 16 projecting from a universal joint 17 in the main supply pipe 18. This main supply pipe is adapted to support rigidly in any suitable manner so that the casing may be moved to various directions relative thereto when the frame 9 is not straddled thereabout. An exhaust pipe 19 leads from the opposite end of the casing and this same end of the casing is also fitted with a plug valve 20 for draining purposes.

In order to apply pressure to the casing to insure of an effective vulcanizing action the intermediate portion of the frame 9 is

formed with a threaded opening in which is fitted a threaded and vertically adjustable stem 21, the lower end of which is formed with a bearing 22 designed to be positioned against and exert a downward pressure on the casing 10 when the stem is adjusted through the instrumentality of the handle 23 carried by the upper end thereof.

In Fig. 4 there is shown a slightly modified form of mold, the under surface of which is recessed so as to be accommodated about the sole, heel and boxing portions of a shoe as indicated at 24. The rest of the construction is the same as that shown in the 10 preferred form shown in Fig. 1 with the exception of course that the casing is of a greater length and it is also apparent that when this form is used the shoe tree may be supported farther toward the left at the 15 position shown in the Fig. 1 so as to be disposed as nearly as possible beneath the intermediate portion of the frame 9, as is apparent.

In using the preferred form of the invention as disclosed in Figs. 1 to 3 inclusive, a shoe (not shown) is adapted to be arranged about the supporting tree 3 so that the sole portion thereof is disposed upwardly whereupon the mold 10 which is universally connected as at 17 with the main supply is swung so as to be positioned over the sole portion in such a manner that the sole portion will be accommodated in the recess. Of course rubber or other plastic 30 composition to be vulcanized is adapted to be arranged therebetween. The frame 9 is now swung upwardly and straddled about the casing 10 which latter may be raised slightly to a slanting or tilting position so that the notched lugs may be engaged about the leg or side portions 8 of the frame and subsequently swung to positions as described and as shown in Fig. 1. Finally, the screw 21 is adjusted so that a pressure will be exerted against the mold. During this adjustment of the screw of course the valve 14 is turned on so that steam may be applied to the casing and this coacts with the pressure which is applied to the casing in 45 insuring an effective vulcanizing action.

It is believed in view of the foregoing description that a further detailed description of the operation of the invention is entirely unnecessary. Likewise, it is believed that the advantages of the invention will be 50 readily apparent.

Still further embodiments of the invention

than those herein especially defined may be resorted to as conditions or preference may dictate, as may be in keeping with the hereto appended claims.

Having thus fully described the invention, what is claimed as new and desired to be secured by Letters Patent, is:

1. A device of the character described including a stand, an inverted shoe supporting tree carried by the upper end thereof, a shelf extending laterally from the stand, a universally mounted mold above the tree, notched lugs projecting from the sides of the mold, brackets carried by the shelf, an inverted U-shaped frame having the terminals of its side portions swingably connected to the brackets and designed to be straddled about the tree and the mold and engaged by the notched lugs to coact with the latter in guiding the sliding movement of the mold relative to the tree, a manually operable pressure applying element adjustably mounted in the frame for acting against the mold, and means for applying heat to the mold.

2. A device of the character described including a stand, an inverted shoe supporting tree carried by the upper end thereof, a shelf extending laterally from the stand, a mold including a rectangular casing the under surface of which is shaped to conform to the shape of a half of a sole of a shoe, an inlet pipe connected therewith, a valve in the pipe for controlling the passage of heat to the casing of the mold, means for detachably and universally connecting the pipe with a heat supply, a shelf extending laterally from the stand, a pair of brackets on the shelf, an inverted U-shaped frame having the terminals of its side portions pivoted to the brackets so that the frame may be swung into straddled relation with the tree and the mold, opposed notched lugs projecting from the mold and slidably engaged with the side portions of the frame, an exteriorly threaded stem adjustably mounted in the intermediate portion of the frame, a bearing carried by the lower end of the stem and engageable with the top of the mold casing, and a hand wheel connected to the top of the stem for facilitating adjustment thereof to consequently apply pressure to the mold casing.

In testimony whereof, I affix my signature hereto.

FRANK B. ROSS.
